BASIN COVER

Robert L. Hammond, Los Angeles, Calif.

Application May 20, 1957, Serial No. 660,402

4 Claims. (Cl. 312—209)

This invention relates to an improved basin cover and is more particularly concerned with a cover for a wash basin in a beauty salon, or the like.

In beauty salons and other like commercial institutions it is common practice to provide wash basins in close proximity to the working area for the purpose of washing and rinsing the customers' hair. In accordance with normal construction, the wash basin is mounted adjacent a wall and is associated with suitable shelving or cabinet work within or adjacent the wall and in which various products, articles and tools of the trade are housed and displayed. Every effort is made to make the equipment and overall construction as attractive as possible.

Due to the basic or fundamental unattractiveness of wash basins, efforts have been made to hide them from view when they are not in use. Such efforts have, for the most part, involved the provision of a simple, rectangular basin cover pivotally carried or connected to the wall above the basin and adapted to be pivoted upwardly and rearwardly to expose the basin when it is desired to be used. Such covers, when they are down, provide a suitable bar or tray upon which objects can be placed.

Such covers while having found wide use have several disadvantages, one of which is the fact that when the basin is to be used, the cover must be cleared, that is, any and all material placed thereon must be removed. Another disadvantage is the awkwardness of the operation and the unsightly appearance of such covers when they are lifted out of engagement over the basins. Still another disadvantage of such covers is the tendency for them to drop or swing closed when the basin is in use and thereby injure the customer, beautician, or both.

It is a general object of the present invention to provide a cover adapted to be shiftably engaged over a wash basin to obscure it from view.

It is an object of the present invention to provide an improved basin cover of the character referred to for use in a beauty salon, which cover provides a bar, top or tray to carry and support various articles.

Another object of the present invention is to provide a cover for a basin of the character referred to which is adapted to slide laterally into and out of engagement over a wash basin and having a portion adapted to serve as a closure for a cabinet above the basin.

A further object of the present invention is to provide a cover of the character referred to which is easy and economical of manufacture and which is both effective and dependable in operation and a structure which is safe.

The various objects and features of my invention will be fully understood from the following detailed description of a typical preferred form and application of my invention, throughout which description reference is made to the accompanying drawings, in which:

Fig. 1 is a perspective view of a typical installation of the cover provided by the present invention and showing it positioned above a wash basin and in front of a cabinet.

Fig. 2 is an enlarged detailed sectional view of a por-

2

tion of the construction illustrated in Fig. 1 and taken as indicated by line 2—2 on Fig. 1.

Fig. 3 is an enlarged view of a portion of the construction that I provide taken as indicated by line 3—3 on Fig. 2.

The structure provided by the present invention involves, generally, a cabinet A, a wash basin B, a closure and cover unit C for the cabinet and the basin and mounting means D shiftably securing the unit C to the cabinet.

10 The cabinet A is an elongate vertically disposed rectangular structure having flat, vertically disposed front and rear walls 10 and 11, end walls 12 and a flat horizontally disposed top wall 13. The cabinet A is divided into upper and lower portions X and Y by an elongate horizontally disposed partition 14 spaced below the top wall 13. The portion of the front wall 10 below the partition 14 is plain and unobstructed while the portion of the front wall 10 above the partition 14 is provided with an elongate access opening 15, providing access to the space defined by the upper portion X of the cabinet. In the case illustrated, suitable shelves 16 are provided in the upper portion of the cabinet and suitable glass closure panels 17 are slidably engaged in the opening.

In addition to the foregoing, the cabinet A is provided with a longitudinally disposed rail 18 fixed to the wall 10 to extend from one end of the cabinet to the other. The rail 18 is positioned to occur below the opening 15 in the upper portion of the front wall of the cabinet and above the wash basin B.

25 In the particular construction illustrated, the upper edges of the front wall 10 and the upper edges of the end walls 12 project above the top wall 13 of the cabinet to cooperatively engage and receive a portion of the closure and cover unit C in a manner that will hereinafter be described.

30 In the preferred carrying out of the invention the cabinet is constructed of wood panels and the like and is adapted to be arranged with its back 11 flat against a wall (not shown). Since the particular construction of the cabinet A can vary widely as circumstances require, further detailed description thereof will be dispensed with.

35 The wash basin B is a typical wall mount wash basin of the type or class used in beauty salons and the like, and is shown positioned adjacent the lower portion of the front panel 10 of the cabinet A at a point intermediate its ends and so that it projects forwardly therefrom. The basin B is shown provided with a suitable spigot 20 and hot and cold water valves 21. The spigot and valves project upwardly from the top of the basin in the normal manner and as clearly illustrated in the drawings. The basin with the tap and valves is positioned, as indicated above, below the rail 18 on the front wall of the cabinet.

40 In the preferred carrying out of the invention, the basin B is mounted on the front wall 10 of the cabinet A and the necessary water supply and waste pipes (not shown), connected therewith project through the lower portion Y of the cabinet in a manner as circumstances require.

45 In view of the fact that the particular mounting means for the basin B will vary according to the particular make and style of basin used and since the manner in which the water supply and waste pipes connect with the basin and project through the cabinet will or can vary in each installation, I have not illustrated these features and will not burden this disclosure with further detailed description thereof.

50 The cover and closure unit C that I provide is a substantially L-shaped member having a flat, vertically disposed rectangular closure panel 22 with straight horizontally disposed top and bottom edges 23 and 24 and straight vertically disposed side edges 25, a flat horizontally disposed rectangular cover panel 26 having front

and rear edges 27 and 28 and straight parallel side edges 29 fixed to and projecting from the lower edge of the closure panel and a flat vertically disposed rectangular skirt 30 having straight horizontally disposed top and bottom edges 31 and 32 and vertically disposed ends 33, fixed to and depending from the front edge 27 of the cover panel 26.

The closure panel 22 is positioned adjacent the upper portion of the front wall 10 of the cabinet A to overlie and close a portion of the opening 15 therein. The upper or top edge of the panel 22 terminates above the upper edge of the panel 10 while the lower edge terminates above the basin B and below the rail 18 on the lower portion of the front panel 10 of the cabinet.

The cover panel 26 is a simple flat rectangular member and is fixed to the lower edge 24 of the closure panel 22 by means of suitable angle brackets 34 so that the lower edge of the closure panel abuts the top surface of the cover panel, adjacent the rear edge thereof. The angle brackets 34 are secured to the panels 22 and 26 by means of suitable screw fasteners 35.

The cover panel 26 projects forwardly from the closure panel 22 to normally overlie the top of the basin B and the spigot and valves 20 and 21 related thereto.

The skirt 33 is a simple flat rectangular member fixed to the front edge 27 of the cover panel 26 to depend therefrom and normally overlie the front of the basin B to obscure the basin from view, when the cover and closure unit C is in its normal working position.

The mounting means D adapted to shiftably support the cover enclosure C on the cabinet A is shown as including a track 40 extending along the upper edge of the front wall 10 of the cabinet A and a runner 41 fixed to the top edge 23 of the closure panel 22 and engaging the track. The means D further includes a plurality of laterally spaced vertically disposed rollers 42 fixed to the back side of the panel 22 to engage the top edge of the rail 18 on the front wall of the cabinet and a plurality of laterally spaced horizontally disposed rollers 43 fixed to the back side of the panel 22 and engageable with the front wall 10 of the cabinet below the rail 18.

The track 18 is established by the upper edge portion of the front panel 10 which projects above the top 13 and is shown as including a rearwardly disposed upwardly inclined face 44. The runner 41 on the closure panel 22 is an elongate flat horizontally disposed member fixed to the upper edge 23 of the panel 22 to project rearwardly therefrom and overlie the top of the cabinet and is provided with a downwardly projecting longitudinally disposed rib 45 having a forwardly disposed inclined face 46 opposing and slidably engaging the said rearwardly disposed face 44 on the track. A suitable longitudinally disposed cleat 47 is secured to the top wall 13 of the cabinet to occur adjacent the rear side of the rib 45 on the runner in proper engagement with the track 40. The track and rail 40 and 41 are formed of wood and can be suitably waxed or soaped to allow for free relative sliding and shifting therebetween.

The upper end portions of the end walls 12 of the cabinet A, which portions of said wall project above the top wall 13 of the cabinet, serve as stops and prevent excessive lateral shifting and resulting displacement of the runner from the rail.

The vertically disposed rollers 42 engaging the top of the rail 18 on the front wall 10 of the cabinet A are shown as being rotatably carried by suitable brackets 48, which brackets are secured to the back surface of the closure panel 22. In the particular case illustrated, a suitable spacer member 49 is interposed between the panel 22 and the brackets 48 to properly position the rollers relative to the rail.

The horizontally disposed rollers 43 engaging the front wall 10 of the cabinet A below the rail 18 are rotatably carried by suitable brackets 50, which brackets are secured to the back surface of the closure panel 22. In

the case illustrated, suitable spacer blocks 51 are interposed between the brackets 50 and the panel 22 to properly position the rollers 43 relative to the front wall of the cabinet.

In practice, two or more sets of rollers 42 and 43 are provided on the panel 22 in lateral spaced relationship to each other. It will be apparent that in practice and by selection of particular rollers on structures, the spacer members and blocks 49 and 51 can be varied in thickness and extent or could be dispensed with if desired.

With the above relationship of parts, it will be apparent that the rollers 42 carry the vertical load of the closure and cover unit C and distribute it upon the rail 18 on the front wall 10 of the cabinet A. The rollers 43 hold the lower portion of the unit C in proper spaced relationship with the front wall of the cabinet and prevent it from rubbing or dragging along the said front wall 10, or along the rail 18. The runner 41, engaging the track 40, maintains the upper portion of the unit C in proper spaced relationship with the cabinet and prevents it from shifting outwardly from the cabinet and in such a manner as would result in disengagement of the rollers 42 from the rail 18.

In the particular case illustrated and in order to make the construction more attractive, the front surface of the closure panel 22 is shown provided and covered by a suitable mirror 60, and the side edges of the panel 22 are shown provided with suitable trim members 61 which overlie the edges of the panel and project rearwardly therefrom to occur in close proximity with the front surface of the cabinet, and hide the roller construction and the like from view.

In practice, the unit C that I provide could be related to a wall having no cabinet therein or related thereto, to overlie and obscure a wash basin projecting therefrom. In this carrying out of the invention, the rail and track would be secured directly to the wall.

With the construction set forth above, it will be apparent that I have provided a novel closure and cover construction for a cabinet and wash basin which construction can be easily and conveniently shifted laterally of the cabinet to open and close a compartment in the cabinet, or a portion thereof, and which can be shifted laterally to uncover or to cover and obscure a wash basin related to and projecting from the cabinet. It will be further apparent that with the construction that I provide, the cover panel 26 establishes a suitable shelf or tray upon which articles being used can be placed and is such that when the cabinet is moved, the articles need not be removed from the panel or tray. It will also be apparent that with the construction that I provide, there is no danger of the construction dropping or otherwise shifting in such a manner as would create a hazard to the operator or other persons in close proximity thereto.

Having described only a typical preferred form and application of my invention, I do not wish to be limited or restricted to the specific details herein set forth, but wish to reserve to myself any variations or modifications that may appear to those skilled in the art and fall within the scope of the following claims:

Having described my invention, I claim:

1. A cover for a wash basin projecting forwardly from a flat vertically disposed surface including, an L-shaped unit having a flat vertically disposed panel adjacent the surface and a flat horizontally disposed panel fixed to and projecting forwardly from the said vertical panel to overlie the basin and establish a shelf, a vertically disposed skirt fixed to and depending from the forward edge of the horizontal panel and normally occurring adjacent the front of the basin and mounting means shiftably supporting the unit on the surface and including, an elongate horizontally disposed track on said surface,

a runner at the top of the vertical panel and cooperatively engaging the track, and a plurality of laterally spaced horizontally disposed rollers fixed to the vertical panel at the lower end portion thereof and engaging the said surface, the unit being shiftable laterally of the surface and the basin to cover and uncover the basin.

2. A cover for a wash basin projecting forwardly from a flat vertically disposed surface including, and L-shaped unit having a flat vertically disposed panel adjacent the surface and a flat horizontally disposed panel fixed to and projecting forwardly from the said vertical panel to overlie the basin and establish a shelf and mounting means shiftably supporting the unit on the surface and including, an elongate horizontally disposed track on said surface, a guide runner at the top of the vertical panel and cooperatively engaging the track, an elongate rail fixed to and projecting forwardly from the surface below the track and a plurality of vertically disposed supporting rollers fixed to the vertical panel and engaging the said top of the rail, the unit being shiftable laterally of the surface and the basin to cover and uncover the basin.

3. A wash basin and cabinet unit comprising an L-shaped cover and closure member, a cabinet including a flat vertically disposed front wall with upper and lower portions, said upper portion having an access opening therein, a wash basin fixed to the lower portion of the front wall of the cabinet to project forwardly therefrom, said L-shaped unit including a flat vertically disposed closure panel adjacent the wall of the cabinet to normally overlie and close the opening therein, a flat horizontally disposed cover panel fixed to and projecting forwardly from the closure panel to normally overlie the top of the basin and establish a shelf, a vertically disposed skirt depending from the forward edge of the cover panel to normally occur adjacent the front of the basin, and mounting means shiftably supporting the unit on the wall of the cabinet and including a track on the wall of the

cabinet, a runner at the top of the closure panel and cooperatively engaging the track, and a plurality of rollers fixed to the closure panel and engaging the said wall, the unit being shiftable laterally of the cabinet to selectively open and close the opening in the cabinet and to uncover and cover the basin.

4. A wash basin and cabinet unit comprising an L-shaped cover and closure member, a cabinet including a flat vertically disposed front wall with upper and lower portions, said upper portion having an access opening therein above the basin, a wash basin fixed to the lower portion of the front wall of the cabinet to project forwardly therefrom, said L-shaped unit including a flat vertically disposed closure panel having a forwardly disposed mirror thereon adjacent the wall of the cabinet to normally overlie and close the opening therein, a flat horizontally disposed cover panel fixed to and projecting forwardly from the closure panel to normally overlie the basin and establish a shelf, and mounting means shiftably supporting the unit on the top wall of the cabinet and including a track on the wall of the cabinet, a runner at the top of the closure panel and cooperatively engaging the track, an elongate rail with a flat top fixed to and projecting forwardly from the wall at a point between the opening and the basin, and a plurality of horizontally disposed rollers fixed to the closure and engaging the said wall below the rail and a plurality of vertically disposed rollers fixed to the closure panel and engaging the top of the rail, the unit being shiftable laterally of the cabinet to selectively open and close the opening in the cabinet and to uncover and cover the basin.
